JOHN D. WALLACE, OF CHICAGO, ILLINOIS, ASSIGNOR TO J. D. WALLACE & CO., OF CHICAGO, ILLINOIS, A CORPORATION OF ILLINOIS.

SAWING APPLIANCE.

1,314,291.

Specification of Letters Patent. Patented Aug. 26, 1919.

Application filed July 12, 1918. Serial No. 244,539.

To all whom it may concern:

Be it known that I, JOHN D. WALLACE, citizen of the United States, residing at Chicago, in the county of Cook and State of Illinois, have invented certain new and useful Improvements in Sawing Appliances; and I do hereby declare the following to be a full, clear, and exact description of the invention, such as will enable others skilled in the art to which appertains to make and use the same.

My invention relates to sawing appliances, and more particularly to novel means for adjusting a circular saw with reference to the saw-table, for effectively guarding the saw, and for deflecting the refuse stock to avoid its being caught by the saw and thrown against the operator. In one of its general aspects, my invention aims to permit various vertical and angular adjustments of the saw without tilting or in any way changing the position of the saw-table, thereby enabling the operator to work constantly in substantially the same position and likewise maintaining the desired lighting regardless of the adjustments of the saw. In another aspect, my invention relates to guards for circular saws, and aims to provide a guard which will be equally effective regardless of the height or angle at which the saw table may be adjusted with respect to the saw, which will automatically be forced out of its guarding position by the stock when the latter is being sawed and which will automatically return to its initial guarding position after each sawing operation; which will effectively guard the periphery as well as the side of the teeth of the saw, and which will automatically deflect the waste part of the stock when the guard is returning to its initial position. Furthermore, my invention aims to provide an adjustable saw mounting, as well as a guard and a mounting for the latter, which will all be free from complications, cheap and easily assembled. It also aims to reduce the friction between the stock which is to be sawed, and the portion of the guard engaged thereby, so as to minimize the resistance offered by the guard during the sawing operation. Furthermore, my invention aims to provide a guard which will be continuously disposed close to the saw and which will automatically adjust itself to an effective guarding position when the position of the

table is shifted with respect to the saw. Still other objects will appear from the following specification, and from the accompanying drawings, in which—

Figure 1 is a fragmentary vertical section through a guarded circular sawing appliance embodying my invention. 60

Fig. 2 is a vertical section taken at right angles to that of Fig. 1, from the line 2—2 of the latter and with the saw and the saw- 65 clamping washers omitted.

Fig. 3 is a plan view corresponding to Fig. 2.

Fig. 4 is an enlarged vertical section showing the arrangement of the guides for 70 the cradle which supports the motor, guard and saw.

Fig. 5 is a detail of the shaft end of the guard.

Fig. 6 is a fragmentary front elevation 75 of the saw, drawn on a smaller scale than Fig. 1 and showing the saw tilted with respect to the table.

Fig. 7 is a fragmentary section, drawn on a smaller scale than Fig. 2 and showing the 80 guard in both of its extreme operative positions when the saw is lowered from its position of Fig. 2 with respect to the table.

Fig. 8 is a fragmentary detail showing a drive pulley as substituted for the motor of 85 Figs. 1 and 6.

Fig. 9 is a fragmentary vertical section showing the manner in which the stop element on the guard underhangs the waste portion of the stock and deflects the latter. 90

Fig. 10 is a fragmentary view of the forward end of a guard showing another shape of stop element.

Heretofore, it has been customary in appliances of this general class either to provide only for a relative vertical adjustment of the saw and the saw-table (thereby affording different depths of cut of the saw, but not permitting cuts to be made other than at right angles to the top of the saw-table), or to tilt the table itself while maintaining the arbor of the saw horizontal. 95

This tilting of the table is objectionable for many reasons, one being the difference in position which it requires the operator to take according as the table is shifted, thereby making him work at a disadvantage. Another objection is the interference of the tilting with the proper light upon the work; also, the tendency of the wood to slide down 110

an incline, thereby causing some part of the original stock to catch on the saw and possibly to be thrown off by the saw with sufficient violence to cause accidents. Moreover, 5 a tilting of the table necessarily limits the size of the stock which can be handled upon the saw table to such lengths as will not strike the floor at the bottom of the incline formed by the top of the saw table, thus 10 preventing the making of angular cross-cuts in long pieces of stock. So also, the tilting of the table has generally interfered with the effective use of guards which were otherwise serviceable when a tilting of the table was 15 not attempted.

In overcoming these and other objections to the appliances heretofore in use, I employ a stationary table which is continuously maintained in a fixed and horizontal 20 position, thereby permitting the operator to work continuously in the same position, and with the same lighting arrangement, and to make cross-cuts in stock of any desired length. Then I provide a mounting for the 25 saw and preferably a joint mounting for the saw, the guard, and a driving element connected to the saw; and I provide simple means for adjusting this joint mounting so as to raise or lower the saw with respect to 30 the table, and so as to tilt the saw at any desired angle. I also provide means associated with the guard for automatically returning the guard to its initial guarding position when the saw has formed its cutting 35 operation, for automatically shifting this initial position of the guard according to the adjusting of the saw with respect to the saw, and for deflecting the waste part of the stock during the return movement of 40 the guard to its initial guarding position.

For example in Fig. 1 the saw table 1 (which is mounted on legs or other supporting means not shown in the drawings) carries a box type of fence 2 and has a slot 45 extending parallel to this fence. This slot is wide enough for the projecting therethrough of a circular saw 3 and of the guard 4. The saw 3 is mounted on an arbor 5 journaled in a bearing 6, which bearing 50 is also shown as carrying the frame of an electric motor 7 having its armature directly connected to the arbor 5. The bearing 6 and the parts thus carried thereby are mounted on a cross-bar 8 sliding upon 55 guide rods 9 on a cradle 10, and a swivel-headed screw 11 interposed between the cradle 10 and the cross-bar 8 (or the bearing 6 which is rigid with respect to the said cross-bar) enables the bearing 6 and 60 the parts carried thereby to be adjusted vertically with respect to the cradle.

The cradle 10 has forked ends 12 straddling segmental supports 13 carried by the table 1 and substantially coaxial with the 65 line along which the circular saw 3 inter-

sects the upper surface of the table 1. The cradle 10 is connected by suitable means, such as a link 14 and a swivel-headed screw 15, with a rigid part 26 of the frame work of the table (as shown in Fig. 6), so that 70 the cradle may readily be rocked on its guides about the said axis, thus tilting the saw to any desired angle, as for example that of Fig. 6. With the parts arranged as described, it will be obvious that the 75 arbor carried by the saw may be moved either toward or away from the table top 1, thereby varying the distance to which the saw 3 projects above the table; also, that this arbor may be adjusted independently 80 of the aforesaid adjustment, to assume varying angles with the table top.

To guard the exposed portion of the saw, I pivot a swinging guard 4 upon the bearing 6, thereby continuously maintaining the 85 guard in proper concentric relation to the saw arbor regardless of the height or angle to which the latter is adjusted with reference to the saw table. The guard 4 desirably consists of a substantially segmental 90 sheet metal punching equipped at its periphery with a flange 35 overhanging the peripheral edge of the saw 3 and directed toward the fence 2. At its inner end, the guard 4 desirably has an offset portion 95 terminating in an annular flange 16 which flange houses and is secured to a ring 17 journaled upon the end of the bearing 6 which faces the saw. This end is desirably turned to a diameter matching the bore of 100 the ring 17 and also is equipped with an annular groove 18 spaced from the end of the said bearing portion and adapted to receive radially inwardly extending lugs 19 upon the said flange 16 of the guard, as 105 shown in Figs. 1 and 5.

The flanged end of the guard also carries an ear 20 affording attachment for a spring 21 connecting the guard with a pin mounted on the cross-bar 8, as shown in Figs. 2 and 110 7. At its forward end, the guard is equipped close to its periphery with a suitable nose or projection extending laterally beyond the slot in the table and hence adapted to engage the upper surface of the table 115 and thereby limit the swinging of the guard in one direction. For this purpose, I desirably employ a roller 22 as shown in Fig. 3, and I widen the rear end of the slot so as to permit the ready passage of the roller 120 through the same when the guard is swung back as shown in dotted lines in Fig. 7. This roller is desirably comparatively small in diameter and substantially flush with the flange 5 of the guard, the function of the 125 roller being to reduce the friction between the forward end of the guard and the stock which engages this end when it is being slid upon the surface of the table toward the saw. Moreover, the spring 21 preferably 130

is so arranged as to increase in effective resistance to the rearward swinging of the guard with the movement of the latter out of its guarding position, so that it will offer a maximum return effort when the guard is swung entirely below the table, and will offer a minimum resistance at the initial engagement of the guard with the stock which is to be sawed. For this purpose, I may use a spiral spring so placed as to wind partly around the offsetting portion of the guard, as shown in Figs. 2 and 7. However, I do not wish to be limited to this or other details of the construction and arrangement here disclosed, it being obvious that the same might be modified in many ways without departing from the spirit of my invention. Thus, while Figs. 1 and 6 show the saw 3 as driven by an electric motor 7 supported entirely by the cross-bar on the cradle, other driving means might be substituted, such as a drive pulley 23 connected by a belt 24 to a suitably disposed source of power, substantially as indicated in Fig. 8.

With the guard arranged as described, it will be obvious that, since the guard is mounted concentric with and close to the saw, the guard will continuously be supported in desirable operative relation to the saw, regardless of the height or angle at which the saw is adjusted with respect to the saw table. Consequently, the operator does not need to make any separate adjustment for the guard, but merely moves the screws 11 and 15 to afford the desired cutting adjustment for the saw. Then the spring 21 and the roller 22 coöperate with the pivoted mounting of the guard to maintain the latter in proper operative position. That is to say, when the saw arbor is lowered with respect to the table, the engagement of the roller 22 with the top of the table automatically swings the segmental guard backward from the position of Fig. 2 to that of Fig. 7, or to a point corresponding to the lowering of the saw arbor. When the saw is not in use, the spring 21 continually holds the roller 22 upon the upper surface of the table forwardly of the saw, and does so regardless of any tilting of the saw, as will be evident from Fig. 6. Then when the stock 24 which is to be sawed is slid along the table, this stock first engages the revolute nose or roller 22, thereby swinging the guard out of the way against the tension of the spring 21 and eventually forcing the roller 22 below the top of the table 1 as shown in Fig. 8. However, as soon as the rear end of the stock has cleared the saw and moved past the roller 22, the spring 21 will automatically return the guard to its initial position.

To reduce the inertia of the guard, I desirably make the latter of rather light ma-

terial, and I may further lighten the same by perforations as shown in the drawings, thereby making the guard quite sensitive, in order that it may be quickly returned to its initial guarding position when the cut is finished or in case the stock is withdrawn in the event of an accident. Also, I desirably place the nose or other movement-limiting projection carried by the guard upon the side away from the saw, so that when the stock passes over the guard and depresses the latter as shown in dotted lines in Fig. 7, this nose or projection will underhang only the waste portion of the stock. For this same reason, I desirably do not carry the flange 35 on the guard beyond the teeth of the saw, though it may terminate flush with these teeth as shown in Fig. 1. Consequently, when the stock has been fed sufficiently along the table for the saw to complete its cut, the continued pressure of the operator's hand upon the portion of the stock guided by him will not interfere with the returning of the guard to its initial guarding position, thus protecting the operator between the time when the cut is finished and the time when the stock is moved entirely clear of the saw. On the contrary, the detaching of the waste part of the stock from the part guided and depressed by the operator will permit the upward thrust of the spring-pressed guard to raise and deflect the waste portion of the stock (as shown for example in Fig. 9), thereby moving this waste portion out of the way, so that it cannot catch in the teeth of the saw and possibly cause accidents.

To facilitate the attaching of the guard to the end of the bearing on which it is journaled through the ring 17, I desirably cut away portions of the end of the bearing on which this ring is journaled, as shown in Fig. 7, thereby affording longitudinal grooves through which the lugs 19 may be moved into alignment with the peripheral groove 18 on the bearing when the guard is swung so far out of its position of Fig. 7 that the left hand lug 19 of that figure aligns with the right hand groove in the bearing of the same figure. This is done before the spring 21 is attached to the guard, the longitudinal grooves in the end of the bearing being preferably so narrow that the lugs 19 will not move out of the groove 18 during the swinging of the guard through its normal range of movements between its operative and inoperative positions.

However, while I have shown and described the particular mounting of the guard, and have described the projection or nose upon the guard as a roller, I do not wish to be limited to these or other particulars here disclosed. For example, the nose might consist of a non-circular revolute element as shown in Fig. 10, thus afford-

ing a flat bearing on the top of the table, or such a stop element might be riveted firmly instead of being revoluble. Likewise, it will be obvious that even with the use of a 5 revoluble stop and stock-engaging element, a continued feeding of the stock causes the latter later on to engage part of the guard itself.

I claim as my invention:

10 1. A saw-table, a circular saw, driving means for rotating the same, a guard normally disposed for guarding the exposed portion of the saw; a unitary mounting for the saw, driving means and the guard; and 15 means for adjusting the unitary mounting with respect to the saw-table without disturbing the operative relation of the driving means and the guard to the saw.

20 2. In combination with a saw-table having a slot therein, a supporting member disposed under the saw-table and mounted on the latter for rocking movement about an axis disposed within said slot and parallel to the latter, means for holding the supporting member in any position to which it may be rocked, and coöperating members carried by the supporting member and including a circular saw and a guard in operative relation thereto, both the saw and the 25 guard normally projecting through the said slot, the guard being adapted to be moved out of its projecting position by the feeding of the stock to the saw.

30 3. In combination with a saw-table having a slot therein; a group of members including a saw arbor, a circular saw fast on the arbor, and a guard movable with respect to the saw; an arcuate guide disposed below the table and concentric with an axis 35 disposed in the slot and longitudinal of the latter; and a mounting movably carried by the guide for supporting the said group of members in a position permitting both the saw and the guard to project through the 40 slot.

45 4. Mechanism as per claim 3, in combination with means for moving the said group of members with respect to the mounting to vary the extent to which the saw projects 50 through the slot.

55 5. A saw-table having a slot, a cradle mounted for rocking movement about the slot as an axis, a bearing carried by the cradle and movable with respect to the cradle radially of the said axis, separate means for tilting the cradle and for moving the bearing with respect to the latter, and a group of coöperating members carried by the bearing and including a circular saw 60 and a guard pivoted coaxially with the saw, both the saw and the guard normally projecting through the slot, the guard including a portion peripherally overhanging a portion of the teeth of the saw and adapted to

be moved through the slot by the feeding 65 of the stock to the saw.

6. Mechanism as per claim 5, in combination with means for maintaining the guard in operative relation to the saw regardless of the adjustments afforded by the tilting 70 of the cradle and the moving of the bearing.

7. A saw-table having a slot, a saw projecting through the slot, an arbor carrying the saw, a guard normally guarding the projecting portion of the saw and adapted 75 to be moved out of its guarding position by the feeding of the stock to the saw, means for permitting a simultaneous tilting of the saw and guard with respect to the table, and means operatively unaffected by 80 the said tilting for normally maintaining the guard in its said guarding relation to the saw.

8. A saw-table, a circular saw, a segmental guard mounted concentric therewith and 85 movable about the axis of the saw; means for simultaneously moving the saw and guard toward or from the table, means for simultaneously tilting the saw and guard with respect to the table, and means responsive to the position of the saw with respect to the table for moving the guard about the 90 axis of the saw.

9. In an appliance of the class described, a circular saw, an arbor carrying the same, 95 a bearing for the arbor having a peripheral groove and a substantially longitudinal slot leading thereto, and a guard pivoted on the bearing and having a portion projecting into the groove and adapted to be inserted 100 in the latter through the said slot.

10. In a sawing appliance, a circular saw, an arbor carrying the same, and means for supporting the arbor and guarding the saw: the said means including as one member a 105 bearing having a substantially cylindrical end portion, and as another member a guard having a substantially cylindrical portion larger than the aforesaid portion, a ring interposed between the cylindrical portions of 110 the said two elements and secured to one thereof, and means associated with the said elements for preventing a relative movement thereof in directions longitudinal of their cylindrical portions.

11. A circular saw, a guard for the same, a saw-table having a slot through which both the saw and the guard project, means for simultaneously moving both the saw and the guard with respect to the saw-table, and means responsive to the said moving for maintaining the forward tip of the guard substantially in a predetermined relation to the most forward exposed saw tooth.

12. The combination with a saw-table 125 having a slot and a circular saw projecting through the slot, of a guard substantially concentric with the saw and also projecting

through the slot and presenting a nose normally disposed for engaging the stock in advance of the saw, means for simultaneously adjusting the positions of the axis 5 of the saw and of the guard with respect to the table, and means for normally maintaining the nose of the guard in its said position regardless of the said adjustment.

13. In combination, a circular saw, a spindle carrying the same, a bearing for the spindle having an annular groove near the end facing the saw, and a saw guard having a portion socketed in the said groove and having another portion overhanging the 10 actively disposed teeth of the saw.

14. In a sawing appliance, a table having a slot, a circular saw projecting through the slot, and a guard pivoted concentrically with the saw and also projecting through the slot 20 and having a segmental edge portion overhanging a part of the periphery of the saw, the guard having a nose normally overhanging one side of the slot forwardly of the saw, and the rear portion of the slot being 25 widened to permit the passage of the nose therethrough when the guard is moved out of its operative position.

15. A circular saw, a guard mounted concentric therewith and movable independently of the saw about their common axis, a table having a slot through which the saw and guard both project, yielding means for normally holding the guard in protective relation to the portion of the saw projecting 30 through the slot while permitting the guard to be moved out of its said relation by the feeding of the stock to the saw, and a projection on the guard out of alignment with a part of the slot through which the normally 35 guarded part of the saw projects, the slot having a lateral enlargement at its rear end to permit the projection to pass below the top of the table and to underhang the waste portion of the stock.

16. In a sawing appliance, a stationary table having a slot, a saw projecting through the slot, an arbor carrying the saw, means supporting the arbor and permitting a tilting thereof with respect to the table, means 45 normally guarding the exposed periphery of the saw and adapted to be moved out of its guarding position by the feeding of the stock to the saw, and means for returning the guarding means to their normal position when the stock has passed the saw, the guarding means having a portion underhanging only the waste part of the stock and disposed for moving only said waste part 50 away from the saw during the returning of the guarding means.

17. A sawing appliance as per claim 16, in

which the refuse-deflecting means also serve as a stop for limiting the return movement of the guarding means.

18. In a sawing appliance, a table having 65 a slot, a saw projecting through the slot, a saw-guard normally guarding the exposed periphery of the saw and adapted to be moved out of its guarding position by the feeding of the stock to the saw, and means 70 for automatically returning the guard to its guarding position when the stock has passed the saw, the guarding means including a portion disposed for laterally deflecting the waste part of the stock during the return 75 movement of the guard.

19. A sawing appliance as per claim 18, in which the guard also operates through the slot, and in which the waste-stock deflecting means normally engage the table to limit the 80 return movement of the guard.

20. In a sawing appliance having a saw protected by a movable guard, single means carried by the guard for limiting the movement of the guard in one direction and for 85 laterally deflecting the waste portion of the stock during the movement of the stock in the said direction.

21. In a sawing appliance, a table having a slot, a saw and a guard therefor both normally projecting through the slot, a guard mounting permitting the guard to be moved to a position entirely below the top of the table by the stock fed to the saw, yielding means continuously resisting the said movement of the guard, the guard having a portion underhanging the waste portion of the stock when the guard is moved to its said 90 position below the top of the table.

22. The combination of a saw-table having a slot, a circular saw projecting through the slot, a movable guard mounted substantially concentric with the saw and also projecting through the slot and having a portion normally engaging the table to limit the 100 movement of the guard in one direction, yielding means continuously tending to move the guard in the said direction, and means for tilting the common axis of the saw and guard with respect to the table without 105 operatively disturbing the said relations of the aforesaid elements.

23. In a sawing appliance, a saw table having a slot; a saw and a guard for the saw concentric with the latter, both projecting 115 upwardly through the slot; and coöperating means for raising or lowering, and for tilting both the saw and the guard simultaneously while maintaining the guard in operative relation to the saw.

Signed at Chicago, Illinois, July 6th, 1918.

JOHN D. WALLACE.
